RECLINING CHAIR

Henry P. Glass, Chicago, Ill.

Application October 24, 1957, Serial No. 48,233

Term of patent 7 years

(Cl. D15—1)

FIG. 1

FIG. 2

Figure 1 is a side perspective view of a reclining chair showing my design as it appears when in a reclining position; and

Figure 2 is a perspective view thereof as seen from the side opposite Figure 1, and as it appears when in an upright position.

The outside of the back of the chair is substantially plain.

I claim:

The ornamental design for a reclining chair, as shown and described.
